CLAIM

The ornamental design for a tread portion of an automobile tire, as shown and described.

DESCRIPTION

U.S. PATENT DOCUMENTS

5,002,109 A *	3/1991	Shepler et al.	.....	152/209.8
D328,582 S *	8/1992	Covert et al.	.....	D12/531
D383,103 S *	9/1997	Ratliff, Jr.	.....	D12/532
D484,845 S *	1/2004	Takahashi et al.	.....	D12/531
D502,911 S *	3/2005	Sato	.....	D12/531
D526,270 S *	8/2006	Miyasaka	.....	D12/532
D551,612 S *	9/2007	Maxwell et al.	.....	D12/532

FIG. 1 is a front view of a tread portion of an automobile tire;
FIG. 2 is a perspective view thereof;
FIG. 3 is a rear view thereof;
FIG. 4 is a left side view thereof;
FIG. 5 is a right side view thereof; and,
FIG. 6 is a fragmentary enlarged view showing the details of
the tread portion thereof.
Broken lines in the drawing figures are intended to show
environmental structure only, and form no part of the claimed
design.
